UNITED STATES PATENT OFFICE.

JACOB L. GRASS, OF OWATONNA, MINNESOTA.

ATTACHMENT FOR SQUARES.

Application filed March 27, 1925. Serial No. 18,700.

My invention has for its object to provide an extremely simple and highly efficient attachment for squares, and to this end it consists of the novel devices and combinations 5 of devices hereinafter described and defined in the claims.

In the accompanying drawings, which illustrate the invention, like characters indicate like parts throughout the several views.

10 Referring to the drawings:

Fig. 1 is an elevation of a try-square having an attachment applied thereto and holding a round member, indicated by broken lines, against one of the sides of the square;

15 Fig. 2 is an end elevation of the square and attachment, as shown in Fig. 1, with the exception that the square has been adjusted to position the rod perpendicular to the square blade;

20 Fig. 3 is a perspective view of the attachment removed from the square;

Fig. 4 is a view corresponding to Fig. 1 but showing a headed member, indicated by broken lines, held by the attachment; and

25 Fig. 5 is a perspective view showing a slight modification of the attachment applied to a carpenter's square, indicated by broken lines.

Referring first to the invention as shown 30 in Figs. 1 to 4, inclusive, the numeral 6 indicates a try-square having a sliding blade, and its leg has at its longitudinal edges T-flanges 7. The attachment comprises a tubular attaching member 8 and an aligning

35 trough 9 hinged thereto. The attaching member 8 is rectangular in cross section and has in one of its sides a longitudinal slot 10 that extends completely therethrough, and which slot is considerably narrower than the 40 internal width of said member to leave retaining flanges 11.

This attaching member 8 is adapted for detachable sliding interlocking engagement with either of the T-flanges 7 of the leg of the square 6, as best shown in Fig. 2. The aligning trough 9 is secured to the attaching member 8 by a long hinge 12. When the attachment is applied to the square 6, as shown in Fig. 1, the aligning trough 9 holds 50 a round rod 13 for parallel swinging movement in the arc of a circle in respect to the sides of the blade of the square 6 and perpendicular thereto. The rod 13 may be held by the aligning trough 9 against either side 55 of the blade of the square 6 or it may be held with one of its ends against one of the

longitudinal edges of the blade of said square, as indicated in Fig. 2, to determine whether or not said end is cut at right angles to the axis of the rod. It is of course understood that the attachment may be used for holding various different articles.

In Fig. 4 there is indicated a round member 14 having a large head 15, and which member is held by the aligning trough 9 to position its head 15 on the outer longitudinal edge of the blade of the square 6 to determine whether or not the same extends at right angles in respect to the axis of the member 14.

Referring now to the modification shown in Fig. 5, the numeral 16 indicates an attaching member that is U-shaped in cross section and adapted to be secured to one of the members of a carpenter's square 17, indicated by broken lines. The sides of the attaching members 16, at their free longitudinal edges, are leaf sprung together so as to engage the square 17 with a yielding clamping action to hold the same where positioned. An aligning trough 18 is secured to the attaching member 16 by a long hinge 19.

From the above description it is evident that the attachment may be very quickly applied to or removed from a square and will positively center and hold the object placed therein so that it may be tested with the square to gauge its several surfaces.

What I claim is:

1. A square attachment comprising an elongated body member applicable to one member of a square so as to be held in parallel arrangement therewith, and an aligning trough hinged to said body member so as to swing about an axis parallel to the member of the square to which the body member is attached.

2. A square attachment comprising an elongated body member applicable to one member of a square so as to be held in parallel arrangement therewith, and an aligning trough hinged to said body member so as to swing about an axis parallel to the member of the square to which the body member is attached and to swing under the other member of the square or on either side thereof.

3. A square attachment comprising an elongated body member arranged for sliding interlocking engagement with one of the members of a square so as to be held in parallel arrangement therewith, and an aligning trough

hinged to said body so as to swing about an axis parallel to the member of the square to which the body member is attached and to swing under the other member of the square or on either side thereof.

4. The combination with a square, of an aligning trough carried by the square and hinged in respect to the inner longitudinal edge of one member of the square for swing-

ing movement about an axis parallel there-¹⁰ to and under the inner longitudinal edge of the other member of the square, whereby an object held in the aligning trough may be positioned against either face of the last noted member of the square or the inner ¹⁵ longitudinal edge thereof.

In testimony whereof I affix my signature.
JACOB L. GRASS.
